(57) **CLAIM**

The ornamental design for a water filtration container, as shown and described.

DESCRIPTION

FIG. 1 is a perspective view of an embodiment of a water filtration container illustrating our new design;

FIG. 2 is a left side elevational view thereof;

FIG. 3 is a right side elevational view thereof;

FIG. 4 is a front side elevational view thereof;

FIG. 5 is a back side elevational view thereof;

FIG. 6 is a top planar view thereof; and,

FIG. 7 is a bottom planar view thereof.

The broken lines in the drawings represent portions of the water filtration container that form no part of the claimed design. All portions of the claim are transparent, as indicated by the oblique line shading. Other shading lines represent the contours.
